FLOAT-VALVE ASSEMBLAGE

Rocco Mazzeo, Emerson, N. J.

Application November 25, 1944, Serial No. 565,123

3 Claims. (Cl. 137—104)

1

This invention relates to a valve structure such as is expressly adapted for disposition atop the feed water delivery pipe in a conventional flush tank, said valve structure, as usual, serving to accommodate the pivoted end of the float arm whereby to open and close the valve element according to the water level in said tank.

Needless to say, I am not unmindful that many and varied types of float-controlled valves have been provided for use at the upper discharge end of the water delivery pipe. However, and notwithstanding this, I have evolved and produced a simple and expedient structural assemblage, which, it is believed, more aptly fulfills the requirements of satisfactory flush tank appliances.

Of outstanding importance is the provision of a detachable and renewable valve seat, said seat being removably attached to the screw-threaded upper end of the water delivery pipe and being properly housed in the sectional valve casing for proper coaction of the reciprocatory valve element therewith.

More specifically, I provide a removable and renewable valve seat unit, that is, a device which includes not only the valve seat per se, but an attaching collar as well as an outstanding flange, the flange being apertured and serving as a satisfactory mount for the sectional casing which surrounds the seat unit and accommodates both the valve element and swingably pivoted end of the float arm.

In addition, it is an object of the invention to utilize the flanged apertured valve seat unit whose marginal edge serves to adapt it for clamping between the companion part of the valve casing.

Other features and advantages will become more readily apparent from the following description and the accompanying illustrative drawings.

In the drawings, wherein like numerals are employed to designate like parts throughout the views:

Figure 1 is a fragmentary view of a portion of a conventional flush tank showing the feed water delivery pipe provided with float-controlled valve means constructed in accordance with the principles of the instant invention.

Figure 2 is a view of the upper portion of said delivery pipe, this broken away and shown in section, the improved valve means, the invention under advisement being shown primarily in section with the valve open.

Figure 3 is a side elevational view showing the pipe, emphasizing the removable valve seat, and the sectional casing for said valve seat, the sections being separated to bring out the construction and relationship of parts.

Figure 4 is a bottom plan view of the hood or conical section of the valve casing.

2

Figure 5 is a top plan view of the removable and renewable seat.

Figure 6 is a view of the cut-off valve with the casing broken away to expose the internal parts.

Figure 7 is a top plan view.

Referring now to the drawings by distinguishing reference numerals, it will be seen that the flush tank, which is conventional, is denoted by the reference character A. The feed water delivery pipe is indicated at B, the same being anchored in the bottom of the flush tank, as at C, by any suitable means. The ball float is denoted at D, and has the usual detachable rod or arm E, this provided with an adjustable block-like mount F.

Reference being had now to the invention itself, I direct attention to Figure 3. Here it will be seen that the upper end of the delivery pipe B is externally screw-threaded, as at 8, to accommodate an internally screw-threaded collar 9 forming an integral part of the valve seat unit 10. The unit 10 includes the valve seat per se 11 which projects upwardly and centrally above the discharge end of the pipe B. Then, in addition, there is an integral disc-like flange 12 provided with apertures 13 suitably shaped and arranged. These are for the back flow of the water which is trapped in the valve casing.

The valve casing comprises a main upper conical section 14 which hoods over the valve seat unit 10, this part 14 being provided with a depending skirt-like flange 15 which is internally screw-threaded and shouldered. The shouldered portion rests upon the marginal portion of the flange 12. The crown portion of the section 14 is provided with a central guide 16 for the stem 17 of the valve 18. The valve stem projects up and between upstanding parallel lugs or ears 19 between which the block F is detachably and hinged mounted, as at 20. The lower rim portion 15 is of hexagonal form to adapt it for the accommodation of a wrench or the like.

Referring again to Figure 3, it will be seen that the lower complemental section of the valve housing or casing is in the form of a ring 21 whose outer perimeter is also of flat-faced form to provide tool grips. The inner perimeter 22 is of a diameter so that it is spaced from the pipe B to provide a water return for water flowing down from the valve casing. The water films down over the pipe B and flows into the flush tank via this route. The ring is also provided with an upstanding annular flange 23, this being screw-threaded and being tapped into the threaded flange or skirt 15, as shown to advantage in Figure 2. The flange 23 engages the under side of the marginal edge of the disc 12, thus binding and clamping both parts 14 and 20 against the flange. As before stated, the flange

thus serves as a supporting mount for the sectional valve casing.

The water entering the pipe B and flowing upwardly through the seat 11 is trapped in the conical chamber and takes a return flow down through the apertures 13 in the disc 12. It floods down over the pipe B by way of the annular opening 22. As the water builds up in the tank, the float arm E acts on the valve 18, the valve comes down on the seat 11 and closes off the supply. Any overflow is taken care of by way of the bypass passage 24 which is formed in the casing section 14 and which discharges through the lateral elbow or fitting 25. In practice, this fitting serves to accommodate an overflow pipe 26, as shown in Figure 1.

Novelty is predicated upon the unit 10 attached to the top of the pipe B (see Fig. 3). Novelty is also based on the sectional casing which encloses the valve unit 10, the casing being made up of the primary parts 14 and 20. Additional novelty has to do with the clamping of the sections 14 and 20 on the marginal edge of the disc 12.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

1. As a new article of manufacture, a bonnet-style valve casing comprising a main upper substantially conical section, the crown portion thereof being provided with a valve stem guide and a pair of upstanding lugs, the latter to accommodate the usual float arm, the lower portion of said section being provided with a depending skirt-like flange, said flange being externally fashioned with flat-faced portions constituting a wrench grip, the interior of the flange being screw-threaded, that portion of the section above said threads being formed into a shoulder, and a supplemental section in the form of a ring centrally apertured and adapted to spacedly surround the upper end portion of a water feeding pipe, the outer perimeter edge of said ring being fashioned into a tool grip, and said ring being provided, at a point spaced inwardly from said outer perimeter edge, with an upstanding screw-threaded flange, the latter being adapted to screw into the screw-threaded skirt carried by said first-named section, and a separate and independent valve seat unit comprising a disc having its outer marginal edge clamped between said shoulder and adjacent edge of the screw-threaded flange on said ring, said disc being apertured and provided with a valve seat nipple, and being further provided with a depending internally screw-threaded collar, said collar being adapted to fit and thread on the upper end of said pipe said collar being the sole means for attaching and supporting the entire valve casing and being of an external diameter less than the central aperture in said ring.

2. As a new article of manufacture, a valve casing comprising a body portion, the top of said body portion being provided with a valve stem

guide and means to accommodate and mount a conventional-type float arm, the basal portion of said casing being provided with a depending, skirt-like flange, and said flange being externally constructed to provide tool-gripping means, the interior of the flange being screw-threaded, the internal portion of said valve casing, at a point above said screw-threaded portion, being formed into an annular shoulder, and a supplemental ring, said ring being centrally apertured and adapted to spacedly surround the upper end portion of a water feeding pipe, the outer perimeter edge of said ring being formed into a tool-grip, and said ring provided, at a point spaced inwardly from said outer perimeter edge, with an upstanding screw-threaded flange, said flange being adapted to screw into the screw-threaded skirt carried by said valve casing, and a separate and independent valve seat unit comprising a disk having its outer marginal edge removably clamped between said shoulder on said ring and the adjacent edge of said upstanding flange, said disk being centrally apertured and provided on its top with an upstanding valve seat nipple and being provided on its bottom with a depending internally screw-threaded collar, said collar being adapted to fit and thread on the upper end of said pipe and constituting the sole means for attaching and supporting the entire valve casing.

3. As a new article of manufacture, a valve casing comprising a body portion, the top of said body portion being provided with a valve stem guide and means to accommodate and mount a conventional-type float arm, the basal portion of said casing being provided with a depending, skirt-like flange, the interior of the flange being screw-threaded, the internal portion of said valve casing, at a point above said screw-threaded portion, being formed into an annular shoulder, and a supplemental ring, said ring being centrally apertured and adapted to spacedly surround the upper end portion of a water feeding pipe, and said ring being provided at a point spaced inwardly from said outer perimeter edge, with an upstanding screw-threaded flange, said flange being adapted to screw into a screw-threaded skirt carried by said valve casing, and a separate and independent valve seat unit comprising a disk having its outer marginal edge removably clamped between said shoulder and adjacent edge of the screw-threaded flange on said ring, said disk being centrally apertured and provided on its top with an upstanding valve seat nipple and being provided on its bottom with a depending internally screw-threaded collar, said collar being adapted to fit and thread on the upper end of said pipe and constituting the sole means for attaching and supporting the entire valve casing.

ROCCO MAZZEO.
